UNITED STATES PATENT OFFICE.

JOSEPH J. MICHALSKI, OF BUFFALO, NEW YORK.

THEFT DETECTOR FOR AUTOMOBILES.

1,412,483.

Specification of Letters Patent. Patented Apr. 11, 1922.

Application filed August 31, 1921. Serial No. 497,347.

To all whom it may concern:

Be it known that I, JOSEPH J. MICHALSKI, a citizen of the United States, residing at Buffalo, in the county of Erie and State of New York, have invented new and useful Improvements in Theft Detectors for Automobiles, of which the following is a specification.

This invention relates to a detector or identifying device for protecting automobiles and similar vehicles from theft.

Its chief object is to provide a device of this character having an improved presence-indicating member.

Another object of the invention is to provide a detachable holder or container for the presence-indicating member of the device.

Still further objects are to provide an identifying device for automobiles which is simple and compact in construction, which is conspicuous, and which can be produced at a moderate cost.

In the accompanying drawings: Figure 1 is a front elevation of the improvement showing the presence-indicating member in position. Figure 2 is a similar view but showing the absence-detecting member in position. Figure 3 is an enlarged sectional side elevation thereof showing the presence-indicating member in position. Figure 4 is a sectional view similar to Fig. 3, but showing the presence-indicating member removed and the absence indicating member in position. Figures 5 and 6 are enlarged transverse vertical sections on the correspondingly numbered lines in Figs. 1 and 2, respectively. Figure 7 is an enlarged horizontal section on line 7—7, Fig. 1. Figure 8 is a horizontal section on line 8—8, Fig. 4. Figure 9 is a perspective view of the holder for the presence-indicating member. Figure 10 is a perspective view of one of the bars of the presence-indicating members.

Similar characters of reference indicate corresponding parts throughout the several views.

This improvement is adapted to be applied to the body of an automobile or similar vehicle where it is conspicuous and clearly visible from either side thereof.

The operative parts of this device are preferably arranged in a rectangular box-like casing or housing 15 which is open at its opposite sides and provided at its lower end with attaching flanges 16 for securing the same to the body of the automobile. The

upper portion of one side of this casing is preferably provided with a swinging door frame 17 hinged at 18 and having a suitable lock 19.

The opposite sides of the casing are provided with suitable means for presenting a characteristic foreground or setting, and for this purpose the open sides of said casing are provided with panes or panels 20, 21, 65 preferably of glass or other transparent material, while the door frame 17 may also be provided with a similar pane or panel 22. As shown in Figs. 1, 2, 5 and 6, the upper and lower portions of the panel 20 are preferably provided on one side thereof with a colored surface 23, such, for example, as red, which is bright and conspicuous, while the central or intermediate portion 24 of said panel is left transparent. The corresponding lower portion of the panel 21 is provided with a similarly colored surface 25, while its upper portion 26 corresponding to and in line with the central portion 24 of the panel 20, is left transparent. The door panel 22 is provided with a like-colored surface 27 corresponding to and in line with the upper colored surface 23 of said panel 20. Thus, on either side of the casing there is a certain transparent bar or portion and above and below the latter there are portions of a conspicuous color forming a characteristic setting or ground for the indicating members of the device.

Arranged within the casing 15 and movable into and out of register with the transparent portions of the panels 20, 21, are two detecting or indicating members 28, 29, the former of which is adapted to indicate the owner's absence from his car and the latter the presence in the car of the owner or some authorized person. These indicating members are of the proper dimensions to occupy the area covered by the transparent portions 24, 26 of the corresponding panels of the casing. The absence-indicating member 28 is of the same color or characteristic nature as the colored portions of the panels 20, 21, 22, while the presence-indicating member 29 is of a contrasting color or of a different characteristic nature than said member 28 and said panels, and is preferably provided with a highly finished reflecting surface. Furthermore, these indicating members are preferably arranged to move in unison, so that when one is set in its operative or indicating position,

the other is automatically set in its inoperative or non-indicating position, and the preferred means for accomplishing this result are constructed as follows:

- 5 The absence-indicating member 28 is guided for vertical movement on upright posts 30 arranged in the bottom of the casing 15, said posts passing through corresponding openings 31 in the base of said member and being provided at their upper ends with heads 32 which serve to limit the upward movement of the indicating member. Coil springs 33 tend to project the latter to its operative or indicating position.
- 10 15 The presence-indicating member 29 is adapted to control the movement of the absence-indicating member 28 as it is moved into and out of its operative position and, as shown in Figs. 3, 5, 7 and 10, the same
- 20 preferably consists of a movable horizontal head plate 34 from which depend a plurality of vertically disposed bars or units 35 which may be of any desired shape in cross section and which are preferably highly finished.
- 25 30 35 These bars may be rigidly secured at their upper ends to said head plate in any appropriate manner, and they are arranged so that their upright edges overlap the corresponding sides of adjacent bars to produce a continuous and uninterrupted surface, as shown in Fig. 3. The head plate is guided for vertical movement in a suitable holder, housing or container 36 which may be detachably secured within the upper portion

limit the upward movement of the head plate in said holder.

In order to hold the head plate and its detecting bars, which form the presence-indicating member of the device, in their depressed or operative position, as shown by full lines in Fig. 3, the holder is provided with suitable yielding locking latches 45 and the head plate is provided with companion locking lips 46 which are adapted to automatically interlock with said latches when said head plate is pushed downwardly. Upon releasing the latches by pushing them inwardly from engagement with their locking lips, the head plate and its detecting bars are automatically elevated by the springs 42 to the position shown by dotted lines in Fig. 3.

Any suitable means may be employed for detachably securing the holder 36 within the casing 15, but as shown in Figs. 3, 4, 5 and 8, these means preferably comprise a horizontal supporting plate 47 extending substantially the full width and depth of the casing and attached at its ends thereto, said plate being located above the transparent portions 24, 26 of the corresponding panels 20, 21. The upper side of this plate is provided with a socket or recessed portion 48 to receive the lower end of the holder. The lower front edge of the latter is provided with a forwardly projecting tongue or lip 49 which is adapted to engage a corresponding groove 50 in the front wall of the socket 48, while the lower rear side of the holder is provided with a groove 51 which is adapted to interlock with a bow spring 52 attached at its ends to the rear wall of said socket. As shown in Figs. 5 and 7, this socket is wider than the width of the holder 36, so that in inserting the latter therein, the groove 51 thereof is first engaged with the spring 52 and then pushed rearwardly, compressing said spring and allowing the tongue 49 to clear the opposing wall of the socket, after which the holder is permitted to move forwardly by the spring to cause said tongue to interlock with the corresponding groove 50 in the socket. The removal of the holder from its socket is effected by reversing the steps just described.

In their elevated position, the push rods 40 project a suitable distance below the base of the holder and are adapted to enter alining openings 53 arranged in the base plate 47. The detecting bars 35, in their elevated position, preferably terminate substantially flush with the bottom of the holder and are adapted to pass through correspondingly-shaped openings 54 in the base plate when said bars are moved to their operative position. To facilitate the bars entering these openings, their lower ends are preferably pointed as shown at 55.

It will be noted that the presence-indicat-

ing member 29 and its holder 36 are preferably removable from the casing 15 through the door 17 while the absence-indicating member 28 is permanently arranged within 5 the casing and dependent on said first-named member for moving it to its respective positions. Upon elevating the presence-indicating member through the medium of the head plate 34, the absence-indicating member is 10 automatically elevated by its springs 33 to the position shown in Figs. 4 and 6, while upon depressing said presence-indicating member to its operative position shown in Figs. 3 and 5, the absence-indicating member is forced downwardly to its inoperative position by the push rods 40 and hidden from view between the lower colored portions of the panel 20, 21. In this position, the presence-indicating member is clearly 15 visible from opposite sides of the casing through its transparent portions 24, 26, and the same stands out conspicuously against the contrasting red setting or ground of 20 said casing.

25 By mounting the presence-indicating member 29 within the detachable holder 36, the highly finished bars 35 thereof are protected against injury when not in use. Furthermore, by detachably securing this 30 holder within the casing in the manner shown, the supporting plate 47 acts as a baffle and renders it impossible for unauthorized persons to practice deception by the use of other indicating members.

35 To permit of varying the presence-indicating members for different automobiles, so that their bars 35 fit only the corresponding openings 54 in the base plate 47, said bars and their alining openings may be made 40 of different shapes and sizes in cross section.

As shown in Figs. 1 and 2, the colored portions 23, 25 and 27 of the panels 20, 21 and 45 22, may be provided with an additional mark or character of identification, for instance, a letter 56 of a color contrasting with said colored portion. The presence-indicating member may also be provided with a corresponding character or letter 57 of the same color as said first-named character. By 50 this arrangement, the device not only indicates through the medium of the presence-indicating member standing out against a contrasting setting or ground, but also by the corresponding identification marks 56 and 57.

55 In the use of this device, when the owner or other authorized person occupies or drives the automobile, he sees to it that the presence-indicating member 29 is in its operative 60 position in the casing and that the door 17 is locked. In this position, which is shown in Figs. 1, 3 and 5, said member stands out conspicuously against the contrasting red ground formed by the colored portions of the 65 respective panels 20, 21 and 22, serving as an

indication to policemen and others that the vehicle is occupied by an authorized person. When the car is left standing or parked, the owner unlocks the door of the casing, elevates the indicating member 29 within its 70 holder 36 as previously described, whereupon the absence-indicating member 28 automatically springs upward to its operative position shown in Figs. 2, 4 and 6, after which he removes said holder from the casing and 75 again closes the door and locks it. In this position, said absence-indicating member is visible through the transparent portions 24, 26 of the casing and forms, together with the colored portions 23, 25 and 27 thereof, a uniformly and completely colored surface or ground indicating that the owner has left the car. Should the car be traveling along the streets with the device in this position, it will arouse the suspicion that the vehicle 80 is being stolen and patrolmen and others can therefore promptly take the necessary steps to arrest the thief.

I claim as my invention:

1. A theft detector for automobiles and 90 the like, comprising a casing having a portion of one of its walls provided with a characteristic ground while another portion thereof is transparent, indicating members arranged in said casing and movable into 95 and out of register with the transparent portion of said casing, one of said members being permanently arranged within said casing, and a holding device for the other indicating member detachably mounted in said 100 casing, one of said members being of the same identity as said ground and indicating the owner's absence from the automobile, and the other member being of a different 105 characteristic nature from said ground and indicating the owner's presence in the automobile.

2. A theft detector for automobiles and the like, comprising a casing having a portion of one of its walls provided with a 110 characteristic ground while another portion thereof is transparent, an indicating member arranged in said casing and movable into and out of register with the transparent portion of said casing, a holder detachably 115 mounted in said casing, a second indicating member carried by said holder and movable into and out of register with the transparent portion of said casing, one of said members being of the same characteristic nature 120 as said ground and indicating the owner's absence from the automobile, and the other of said members being of a different characteristic nature from said ground and indicating the owner's presence in the automobile.

3. A theft detector for automobiles and the like, comprising a casing having a portion of one of its walls provided with a characteristic ground while another portion 125

- thereof is transparent, an indicating member arranged in one end of said casing and movable into and out of register with the transparent portion of said casing, a holder 5 detachably mounted in the other end of said casing, a second indicating member carried by said holder and movable into and out of register with the transparent portion of the casing and controlling the movement of 10 said first-named indicating member, the latter being of the same characteristic nature as said ground and said second indicating member being of a different characteristic nature from said ground.
- 15 4. A theft detector for automobiles and the like, comprising a casing having a colored portion and a transparent portion, a presence-indicator and an absence indicator yieldingly mounted in said casing and each 20 movable into and out of register with the transparent portion of said casing, one of said indicators constantly tending to assume an operative position and the other constantly tending to assume an inoperative 25 position, and means for holding said indicators in their operative positions, said absence-indicator being of the same color as the colored portion of the casing and said presence-indicator being of a contrasting 30 color.
5. A theft detector for automobiles and the like, comprising a casing having a colored portion and a transparent portion, an absence-indicator of the same color as 35 said colored portion arranged in said casing and movable into and out of register with said transparent portion, a holder detachably mounted in said casing, a presence-indicator of a color contrasting with said 40 colored portion carried by said holder and movable into and out of the same to register with said transparent portion, and means for holding said presence-indicator in its operative position.
- 45 6. A theft detector for automobiles and the like, comprising a casing having a colored portion and a transparent portion, an absence-indicator of the same color as said colored portion arranged in said casing and 50 movable into and out of register with said transparent portion, a holder mounted in said casing, a presence-indicator of a color contrasting with said colored portion carried by said holder and movable into and 55 out of the same to register with said transparent portion, and means carried by said presence-indicator and adapted for engagement with said absence-detector to move the same to its inoperative position.
- 60 7. A theft detector for automobiles and the like, comprising a casing having a colored portion and a transparent portion, an absence-indicator of the same color as 65 said colored portion yieldingly supported in one end of said casing and moving into and

out of register with said transparent portion, a holder mounted in the other end of said casing, and a presence-indicator of a color contrasting with said colored portion yieldingly supported in said holder and movable into and out of the same to register with said transparent portion, said indicators being movable in unison, one into and the other out of operative position. 70

8. A theft detector for automobiles and the like, comprising a casing having a colored portion and a transparent portion, an absence-indicator of the same color as said colored portion yieldingly supported in one end of said casing and movable into and 80 out of register with said transparent portion, a holder mounted in the other end of said casing, a presence-indicator of a color contrasting with said colored portion yieldingly supported in said holder and movable into and out of the same to register with said transparent portion, said indicators being movable in unison, one into and the other out of operative position, and means for holding said indicators in their operative 85 positions.

9. A theft detector for automobiles and the like, comprising a casing having a colored portion and a transparent portion, an absence-indicator of the same color as said 90 colored portion arranged in said casing and movable into and out of register with said transparent portion, a holder mounted in said casing, a presence-indicator of a color contrasting with said colored portion carried by said holder and movable into and out of the same to register with said transparent portion and interlocking devices carried by said holder and said presence-indicator for holding the latter in its operative 95 position. 100

10. A theft detector for automobiles and the like, comprising a casing having a colored portion and a transparent portion, an absence-indicator of the same color as said 110 colored portion yieldingly supported in one end of said casing and movable into and out of register with said transparent portion, a holder mounted in the other end of said casing, a presence-indicator of a color contrasting with said colored portion yieldingly supported in said holder and movable into and out of the same to register with said transparent portion, said indicators being movable in unison, one into and the other out of 115 operative position, means carried by said presence-indicator and adapted for engagement with said absence-detector to move the same to its inoperative position, and interlocking devices carried by said holder and said presence-indicator for holding the latter in its operative position and said absence-indicator in its inoperative position. 120

11. A theft detector for automobiles and the like, comprising a casing having a col- 125

ored portion and a transparent portion, a supporting plate arranged transversely of said casing above the transparent portion thereof and provided with an opening, an 5 indicating member arranged in the lower portion of said casing and movable into and out of register with said transparent portion, and a second indicating member detachable from said casing and movable 10 through the opening in said plate into and out of register with said transparent portion, one of said members being of the same color as the colored portion of said casing, and the other being of a contrasting color.

15 12. A theft detector for automobiles and the like, comprising a casing having a colored portion and a transparent portion, a supporting plate arranged transversely of said casing above the transparent portion 20 thereof and provided with an opening, an indicating member arranged in the lower portion of said casing and movable into and out of register with said transparent portion, an indicator holder detachably mounted 25 on said supporting plate, a second indicating member carried by said holder and movable through the opening in said plate into and out of the same to register with said transparent portion, one of said members 30 being of the same color as the colored portion of said casing, and the other being of a contrasting color.

13. A theft detector for automobiles and the like, comprising a casing having a colored portion and a transparent portion, an absence-indicator of the same color as said colored portion arranged in said casing and movable into and out of register with said transparent portion, a holder detachably 35 mounted in said casing, and a presence-detector carried by said holder and comprising a head plate guided for movement in said holder, and a plurality of bars depending from said plate and movable into and out of 40 said holder to register with the transparent portion of said casing, said bars being of a

contrasting color from said colored portion of the casing.

14. A theft detector for automobiles and the like, comprising a casing having a colored portion and a transparent portion, an absence-indicator of the same color as said colored portion arranged in said casing and movable into and out of register with said transparent portion, a supporting plate in 50 said casing above the transparent portion thereof, a holder detachably mounted on said plate, and a presence-detector carried by said holder and comprising a head plate guided for movement in said holder, and a 55 plurality of bars of a contrasting color from said colored portion depending from said head plate and movable into and out of the holder to register with the transparent portion of said casing, said supporting plate 60 being provided with a plurality of openings corresponding in shape to said bars.

15. A theft detector for automobiles and the like, comprising a casing having a characteristic ground, a supporting plate arranged in said casing and having a socket in its upper side, a holder detachably mounted in said socket, and an indicating member movable into and out of said holder relatively to said ground, said indicating member including a plurality of pendant overlapping bars of uniform shape and said supporting plate being provided with corresponding openings for receiving said bars.

16. A theft detector for automobiles and the like, comprising a casing having a characteristic ground, a supporting plate arranged in said casing and having a socket in its upper side, a holder detachably mounted in said socket, an indicating member movable into and out of said holder relatively to said ground, means tending to maintain said indicating member within said holder, and means for holding said member in its projected position.

JOSEPH J. MICHALSKI.
